UNITED STATES PATENT OFFICE.

JOHN M. WADDELL, OF GREENFIELD, OHIO.

PHONOGRAPH.

1,274,640.

Specification of Letters Patent.

Patented Aug. 6, 1918.

Application filed February 14, 1918. Serial No. 217,211.

To all whom it may concern:

Be it known that I, JOHN M. WADDELL, a citizen of the United States of America, and resident of Greenfield, in the county of 5 Highland and State of Ohio, have invented a new and useful Improvement in Phonographs, of which the following is a specification.

An object of my invention is to produce 10 an improved phonograph in which improved instrumentalities are employed for modifying the intensity of the sound waves without producing muffled effects, while simultaneously serving ornamental and useful 15 purposes in an article of furniture other than a phonograph cabinet.

This and other objects are attained in the phonograph described in the following specification and illustrated in the accompanying drawings, in which;

Figure 1 is a front elevation of a phonograph embodying my invention.

Fig. 2 is a transverse sectional elevation taken on the line 2—2 of Fig. 1.

25 Fig. 3 is a plan view of the phonograph embodying my invention, the lid being completely raised.

Fig. 4 is a transverse sectional view taken on the line 4—4 of Fig. 3, the lid being 30 shown in normal raised position.

In the illustrated embodiment of my improved phonograph I have shown a cabinet having the form of an old fashioned drop leaf table, the lid 5 of the phonograph being the table top when in closed position, and the drop leaf of the table forming the sound modifying damper 6 of the phonograph when dropped. Beneath the lid 5 I have provided a box-like container 7 which 35 is divided into two compartments 8 and 9, in the former of which the phonograph mechanism 10 is mounted and in the latter of which the record racks 11 are located.

40 The phonograph mechanism consists of the usual record turn table 12 located above a platform 13 beneath which the motor for rotating the turn table is located, the usual sound box 14 and tone arm 15 which are located above the platform for co-operation 45 with the turn table, and the sound amplifying horn 16 which is located beneath the platform and which has its opening in the side of the container 7 as shown in Fig. 1.

50 Between compartment 8 and compartment 9 I have located two walls 17 and 18 which are spaced apart and between which is lo-

cated a mechanism for controlling the operation of damper 6 from lid 5 or of permitting the movements of these elements to be independent if desired. This mechanism 50 consists of an arm 19 which is pivotally mounted between its ends as shown in Figs. 2 and 4, a link 20 which connects the arm and damper, and a spring 21 which connects the lower end of arm with a bracket 22. The 55 upper end of arm 19 is provided with a roller 23 which is caused to bear upon and roll in contact with a track 24 secured to the under side of lid 5. The track is provided with a portion 25 which the roller engages when 70 the lid is in closed position as shown in Fig. 2, and a portion 26 which is engaged by the roller when the lid is raised as shown in Fig. 4. Link 20 connects arm 19 and damper 6 by means of a pin 27 which engages a notch 28 in the link, and a bracket 29 which is secured to the damper and which 75 pivotally connects with the opposite end of the link.

In compartment 9 the record racks 11 are 80 located and may be of any desired type, the racks shown being preferred since they hold the records in staggered relation to enable them to be conveniently removed. A receptacle 30 is provided for the reception of a 85 record duster.

In the operation of my improved phonograph the lid is raised to the position shown in Fig. 4, spring 21 acting simultaneously 90 to cause roller 23 to assist in the lifting operation and when the roller engages portion 26 of the track 24 the lid is retained in the lifted position. If notch 28 of link 20 has been disengaged from pin 27 previous to lifting lid 5, the notch and pin 28 and 27 95 will engage when the lid has been brought to position shown in Fig. 4. If it is desired to close the lid after engagement of the notch and pin, the lid is lowered and in so doing, the link, through its connection with arm 19, is caused to swing damper 6 outwardly to the position shown in Fig. 2. This results in opening the mouth of the amplifying chamber 16 as shown in Fig. 1, so that the full volume of sound from a record being played, may be had. When the lid is down and the damper raised, a table top of good proportions is obtained, and in order to hold the lid down when pressure is brought to bear upon damper 6, I have 100 provided a catch 31 of any suitable form adapted to secure the lid to the body. 110

Should it be desired to lower the damper independently of the lid movement, the link may be disengaged from arm 19 by pushing upon the link from the under side of the damper when it is in the raised position as shown in Fig. 2, or by disengaging the link from the arm previous to the lowering of the lid, by means of notches 32 and 33 which permit the link to be grasped by the fingers.

10 In my improved construction I have produced a phonograph which provides a sound damper which operates to reduce the volume of the sound without giving it the usual characteristic boxed in effect. This is because of the space 34 provided between the damper and the end of the horn. The sound waves are free to pass out around the bottom and ends of this space, but, because they are interrupted, they do not issue forth in the same intensity as when the damper is raised. When the damper is raised it acts somewhat as a sounding board adapted to aid in the reproduction of the selection being played.

Having thus described my invention, what I claim is:

1. A phonograph consisting of a cabinet having a phonograph mechanism therein, a sound amplifying horn connected with said mechanism and opening in a wall of the cabi-

net adjacent to the mechanism, a sound damper pivotally mounted adjacent to the upper edge of the horn opening, a lid pivotally mounted on the cabinet above the mechanism, and means connecting the lid and the damper, whereby the damper will be raised when the lid is closed and lowered when the lid is raised.

2. A phonograph consisting of a cabinet having a phonograph mechanism therein, a sound amplifying horn connected with said mechanism and opening in a wall of the cabinet adjacent to the mechanism, a sound damper pivotally mounted adjacent to the upper edge of the horn opening, a lid pivotally mounted on the cabinet above the mechanism, and means detachably connecting the lid and the damper, whereby the damper will be raised when the lid is closed and lowered when the lid is raised or whereby the damper may be detached from the lid for independent operation thereof.

In testimony whereof, I have hereunto subscribed my name this eleventh day of February, 1918.

JOHN M. WADDELL.
